LIFTING AND PULLING MECHANISM

Sidney Hinchcliffe, Wylam-on-Tyne, England

Application July 5, 1945, Serial No. 603,339
In Great Britain July 21, 1944

9 Claims. (Cl. 254—167)

1

This invention relates to lifting and pulling mechanism.

The object of the invention is to provide a lifting and pulling gear which will be compact and for its size capable of carrying substantially greater loads than hitherto. Another object of the invention is to provide an intermittent or ratchet type of lifting and pulling mechanism in which a practically infinite ratchet movement may be obtained so that loads may be lifted or lowered with greater delicacy or adjustment than has hitherto been possible. A further object is to provide improved freedom of chain movement in such ratchet form of the mechanism.

The mechanism according to the invention comprises a lifting shaft rotatable in a casing and having rigidly mounted thereon a chain sprocket for carrying the lifting chain, and a driving member for turning the said shaft, while interposed between the said driving member and the casing, and in resilient rubbing contact with the latter, is a clutch member which is in threaded engagement with the said shaft in such a manner that when the driving member is turned to take the load, the movement of the shaft tends to retract the said clutch member and so relieve the pressure between it and the casing, but when the driving member is released from turning effort, and so tends to move in the opposite direction, its movement tends to increase the pressure between the clutch member and the casing, so that the shaft is held.

The resilient contact between the clutch member and the casing may be effected by resilient means interposed between the driving member and the clutch member and connecting the two members so as to form a resilient connection between them with the result that as the driving member is moved the clutch member is resiliently pushed or pulled around with it and is thus always ready for engagement with the casing when the driving member ceases to exert any driving effort, and to disengage when the driving effort is resumed.

According to one form of the invention the mechanism is operated by means of a double pawl and ratchet the one pawl and ratchet being adapted to operate the shaft in one direction and the other pawl and ratchet to operate the clutch in the opposite direction, and in a preferred form of such double ratchet mechanism the pawls comprise radially slidable pawl members mounted in two angularly spaced radial casings projecting from a housing enclosing a ratchet wheel on the shaft and the clutch member on which are formed

2

ratchet teeth in opposite formation to those of the ratchet wheel, the said pawl casings having arranged between them a common transverse cylindrical casing containing a rotatable locking member having formed thereon circumferential grooves into which project portions of the said pawls, and also a segmental recess which leaves a solid segmental portion the ends of which form abutments which are adapted to engage shoulders on the outer portions of the pawls to withdraw the one or the other pawl from engagement with its respective ratchet teeth according to the position of the said locking member, the other pawl being free to operate.

15 The invention will now be described by way of example with reference to the accompanying drawings which show a ratchet form of the mechanism.

In the said drawings:

Fig. 1 is a sectional plan taken on the line I—I of Fig. 2.

Fig. 2 is a section on the line II—II of Fig. 1.

Fig. 3 is an outside elevation.

Fig. 4 is a section on the line IV—IV of Fig. 1.

Fig. 5 is a section on the line V—V of Fig. 3.

Fig. 6 is a partial section on the line VI—VI of Fig. 4.

Referring more particularly to the drawings, the mechanism comprises a casing 1 in which is mounted a lifting driving shaft 2 whose one end projects into the casing and has rigidly mounted thereon a chain sprocket 3. The end of the shaft 2 inside the casing 1 has a journal thereon which is carried in a bearing portion 4a integral with a detachable cover plate 4 which encloses the sprocket 3 inside the casing. The casing 1 is open at its lower portion to allow of the passage of the lifting chain whose centre line is indicated at 5 and having a hook 5a attached thereto. Collars 2a, 2b are formed on this portion of the shaft to prevent its moving axially relatively to the casing.

The projecting portion of the lifting shaft has formed thereon a multi-start thread 2c for a portion of its length. The outer adjacent portion 2d of the shaft is reduced to receive a ratchet wheel 6 which is keyed to the said shaft. This ratchet wheel constitutes the driving member of the mechanism. Between the ratchet wheel 6 and the casing 1 a clutch member 7 is arranged in threaded engagement with the multi-start thread 2c the said clutch member being of slightly less diameter than that of the ratchet wheel 6. Ratchet teeth 7a are formed on the periphery of the clutch member 7. The teeth of the clutch

member 7 and ratchet wheel 6 are oppositely arranged. Two or more clutch discs 8, 9 keyed respectively to the shaft 2 and casing 1 are interposed between the clutch member 7 and the casing 1 to form a plate clutch according to 5 known form, friction rings 10 being interposed between the clutch member 7, discs 8 and 9 and the casing 1.

The mid portion of the shaft 2 is preferably supported in an oil-less bush 11, that is to say 10 an oil secreting bush, to avoid lubrication difficulties.

A common ratchet arm 12 is mounted about the clutch member 7 and the ratchet wheel 6 with corresponding pawls 13, 14 which take the form of cylindrical members slidably mounted in corresponding angularly spaced radial cylindrical casings 15a, 15b in a common housing 15 which is integral with the ratchet arm 12, the said casings projecting from a housing 16 enclosing the ratchet wheel 6 and the clutch member 7, while between and integral with the casings 15a, 15b there is arranged a common transverse cylindrical housing 15c in which is rotatably mounted a cylindrical locking member 17 having formed thereon circumferential grooves 17a, 17b (Fig. 5) into which project flat portions of the pawls 13 and 14 respectively. The pawls are thus prevented from rotating about their own axes. A transverse segmental recess 17c is cut out of the locking member 17 for nearly its total width so as to leave a solid segmental portion the ends of which form abutments which are adapted to engage one or other of the shoulders on the pawls 13, 14 formed by their flats, according to the position of the member 17 which is operated by means of an arm 18 screwed into a transverse bore therein and limited by stops 15d, 15e on the casing 15c. 19 indicates the pawl actuating springs, one only of which is visible in the drawings.

In the position of the arm 18 shown in the drawings the locking member 17 has been turned so that the lower end of its segmental portion has abutted against the outer shoulder of the clutch member pawl 14 and as a result has forced it out of engagement with the teeth on the clutch member, the final movement of the arm 18 causing the end of the segment to move past the pawl shoulder so that the pawl 14 is positively locked without any tendency for its spring to turn the member 17. At the same time the upper end of the segmental portion has moved inwards beyond the inner limit of the shoulder on the pawl 13 which is thus in the space 17c, so that the said pawl is free to operate. In order to ensure against unintentional turning of the member 17 near the ends of the segmental portion nicks are formed at 17d, 17e with which the pawl shoulders are adapted to engage under the pressure of their springs.

The assembly of the above pawl control device is exceedingly simple and is effected prior to the passing of the casing 16 over the ratchet wheel and clutch member. The locking member 17 is first inserted and is located in its correct lateral position by means of a locating screw 49 having a reduced inner portion which is an accurate sliding fit in one of the circumferential grooves say 17b as shown. It is necessary to have the member 17 correctly located in order to ensure the free reciprocating movement of the pawls in the grooves 17a, 17b in which their flat portions are easy sliding fits. The member 17 is then turned so that the space 17c coincides

with the interior of one of the casings 15a, 15b, so that its respective pawl 13 or 14 and its spring may be inserted therein so that its shoulder is within the space 17c. The member 17 is then turned until the space 17c coincides with the interior of the other casing when the other pawl and its spring are inserted in the said casing, the first pawl having as a result of such movement been forced further along the casing by the end of the segmental portion of the member 17. The member 17 is then turned until the bore for receiving the arm 18 comes between the stops 15d and 15e and the said arm inserted. The arm 18 thus locks the member 17 from turning far enough to release the pawls beyond their predetermined limits of travel, so that the member 17 in its turn acts as an effective lock for the pawls. The whole assembly is thus effectively held by means of the arm 18 and the locating screw 19.

The driving shaft 2 is further reduced to form a screw-threaded portion 2e which receives a holding down nut 20 which is journaled and flanged to retain a hand wheel 21 for effecting continuous movement of the mechanism when paying in or out of the chain has to be effected. The said hand wheel has a segmental slot 21a for accommodating a lateral pin 22 which projects from the clutch member 7 through a segmental slot 6a in the ratchet wheel 6, and for accommodating a similar pin 23 on the ratchet wheel 6 arranged at a small angle from the pin 22. The nut 20 is locked to the spindle by means of a pin 24 or other locking means. The ratchet wheel 6 has a concentric boss 6b around which is wrapped a helical spring 25 of which the one end is connected to the clutch member pin 22 and the other end to the ratchet wheel pin 23.

The operation of the mechanism is as follows: when it is desired to lift a load, the ratchet wheel pawl 13 is engaged with the ratchet wheel 6, and the clutch pawl 14 disengaged as above described. The lever 12 is then operated so that the ratchet wheel 6 is driven and the shaft 2 is turned. Owing to the clutch member 7 being pressed against a friction ring 10 and disc 9, it tends to lag, and as the shaft 2 turns, its screw thread 2c tends to bring the clutch member 7 out of engagement with the casing 1 by releasing the pressure on the clutch discs 8 and 9, so that the shaft 2 is free to operate. The rotation of the shaft 2 tends to withdraw the clutch member 7 which then, owing to the resilient connection of the spring 25, trails after the ratchet wheel 6 and is thus maintained out of effective engagement with the casing 1, it actually making a light rubbing contact. When the lever is released the tendency of the shaft 2 to move in the opposite direction under the load, 60 at once, owing to such rubbing contact, draws the clutch member 7 into engagement with the casing 1 through the clutch plates 8, 9. The shaft 2, and consequently the load, is thus held against turning during the return movement of the operating lever 12. On reversing the lever again, the same sequence of movements of the mechanism occurs, and so on throughout the lifting period.

When it is desired to lower a load, the pawl operating device is operated so that the ratchet wheel pawl 13 is withdrawn and the clutch pawl 14 engaged with the ratchet teeth 7a on the clutch member 7. From the above description it will be seen that when the shaft 2 is stationary the clutch member 7 is always engaged, so that the

load is held. To lower the load, the operating lever 12 is moved in the direction reverse to that of lifting. This causes the clutch member 7 to disengage with the casing 1 so that the shaft 2 is free to turn but as the turning of the shaft 2 is relatively to the clutch member 7 always tends to draw the clutch into full engagement, the movement of the shaft 2 will only continue while the lever 12 is being moved. On the return movement of the lever 12, the shaft 2 is held by the self engagement of the clutch member 7 as above described.

When it is desired to pay out or pay in the chain preparatory to carrying a load, this may be done quickly by turning the hand wheel 21. The effect of this is to engage one or other of the lateral pins 22, 23 projecting from the clutch member 7 and the ratchet wheel 6 respectively. For example, if it is desired to lower the hook, the pawls 13, 14 are set as for lowering a load, that is to say so that the ratchet wheel pawl 13 disengages and the clutch member pawl 14 engages. The hand wheel 21 is then turned in an anticlockwise direction. This brings the lower end of the slot 21a against the pin 22 and has the effect of withdrawing the clutch member and pressing it against the ratchet wheel so that the shaft is turned. This turning continues as long as the hand wheel turns. Directly the hand wheel 21 is arrested, the clutch member 7 engages the casing 1 and further payment out of the chain is prevented. If it is desired to draw in the hook, then the clutch pawl 14 is disengaged, the ratchet wheel pawl 13 is engaged, and the hand wheel 21 is turned in a clockwise direction. This has the effect of bringing the upper end of the slot 21a against the ratchet wheel pin 23, so turning the ratchet wheel 6 which has the further effect of relieving the clutch pressure and freeing the shaft 2, the clutch member 7 thereafter turning with the ratchet wheel 6 owing to its being trailed by the spring 25. The movement of the shaft 2 continues so long as the hand wheel 21 is rotated, but directly the movement of the hand wheel is arrested, then the weight of the hook tends to turn the shaft 2 in the reverse direction with the immediate result that the clutch member 7 again fully engages with the casing 1.

The pitch of the thread 2c is to be such that the clutch member 7 will not revolve when the shaft 2 is turned in the proper direction provided the friction surfaces are originally in contact. This will depend upon the friction and radius of the friction rings 10 and the friction and radius of the thread.

It will be seen that with a relatively small mechanism substantially heavy loads may be handled, for the reason that once the dimensions of its main members—the casing and the shaft—have been decided upon according to the maximum load to be handled, the remaining members may be easily accommodated without affecting the width and diameter of the mechanism. Further, with the form of clutch described, the disengagement thereof requires a minimum of effort by the operator. The advantage of this is particularly noticeable in lowering operations; for in the usual form of clutch comprising a relatively heavy clutch engaging spring whose pressure has to be overcome to disengage the clutch, disengagement requires a substantial effort which has to be sustained throughout the lowering operation.

I claim:

1. Lifting and pulling mechanism comprising a casing, a shaft rotatable in said casing, a chain sprocket mounted on said shaft, a ratchet wheel rigidly mounted on said shaft, said ratchet wheel having a segmental slot formed therein, a clutch member interposed between said ratchet wheel and said casing, said clutch member being in resilient rubbing contact with said casing and in threaded engagement with said shaft, ratchet teeth on said clutch member, said ratchet teeth being oppositely disposed to those on said ratchet wheel, oppositely disposed pawls adapted to engage said ratchet wheel and clutch member respectively, a common operating member for individually retracting said pawls, a pin projecting laterally from said clutch member into the slot in said ratchet wheel, a second pin projecting laterally from said ratchet wheel into the same plane as said clutch pin, and resilient connecting means arranged between said pins so that said clutch member follows the movement of said ratchet wheel.

2. The mechanism according to claim 1, comprising a hand wheel rotatably mounted on said driving shaft, said hand wheel having a segmental slot for accommodating said ratchet wheel and clutch pins so that in the one direction of turning of said hand wheel the one end of the slot abuts against the clutch pin and so withdraws the clutch member and presses it against the ratchet wheel so that the shaft is turned, while in the other direction the other end of the slot abuts against the ratchet pin and so turns the shaft and withdraws the clutch member.

3. The mechanism according to claim 1 comprising a housing enclosing the ratchet wheel and clutch member, pawl casings projecting from said housing, said pawl members being slidably mounted in said pawl casings and adapted respectively to engage the ratchet wheel and clutch members, a common transverse cylindrical casing arranged between said pawl casings, a rotatable locking member in said transverse casing, said locking member having formed thereon circumferential grooves into which project portions of said pawls, said locking member also having formed therein a segmental recess which leaves a solid segmental portion the ends of which form abutments, shoulders on the outer portions of said pawls, said shoulders being adapted to abut against said abutments to withdraw said pawls alternatively from engagement with their respective teeth according to the position of said locking member.

4. The mechanism according to claim 1, comprising a housing enclosing the ratchet wheel and clutch member, pawl casings projecting from said housing, said pawl members being slidably mounted in said pawl casings and adapted respectively to engage the ratchet wheel and clutch members, said pawl members having flats formed thereon, a common transverse cylindrical casing arranged between said pawl casings, a rotatable locking member in said transverse casing, said locking member having formed thereon circumferential grooves into which project said flats of said pawls, said locking member also having formed therein a segmental recess which leaves a solid segmental portion the ends of which form abutments, shoulders on the outer portions of said pawls, said shoulders being adapted to abut against said abutments to withdraw said pawls alternatively from engagement with their respective teeth according to the position of said locking member.

5. The mechanism according to claim 1, com-

prising a housing enclosing the ratchet wheel and clutch member, pawl casings projecting from said housing, said pawl members being slidably mounted in said pawl casings and adapted respectively to engage the ratchet wheel and clutch members, a common transverse cylindrical casing arranged between said pawl casings, a rotatable locking member in said transverse casing, said locking member having formed thereon circumferential grooves into which project portions of said pawls, said locking member also having formed therein a segmental recess which leaves a solid segmental portion the ends of which form abutments, shoulders on the outer portions of said pawls, said shoulders being adapted to abut against said abutments to withdraw said pawls alternatively from engagement with their respective teeth according to the position of said locking member, said segmental portion being nicked near its ends for engagement with said pawl shoulders.

6. The mechanism according to claim 1, comprising a housing enclosing the ratchet wheel and clutch member, pawl casings projecting from said housing, said pawl members being slidably mounted in said pawl casings and adapted respectively to engage the ratchet wheel and clutch members, a common transverse cylindrical casing arranged between said pawl casings, a rotatable locking member in said transverse casing, said locking member having formed thereon circumferential grooves into which project portions of said pawls, and a pin in said transverse casing projecting a sliding fit in one of said grooves, said locking member also having formed therein a segmental recess which leaves a solid segmental portion the ends of which form abutments, shoulders on the outer portions of said pawls, said shoulders being adapted to abut against said abutments to withdraw said pawls alternatively from engagement with their respective teeth according to the position of said locking member.

7. The mechanism according to claim 1, comprising a housing enclosing the ratchet wheel and clutch member, pawl casings projecting from said housing, said pawl members being slidably mounted in said pawl casings and adapted respectively to engage the ratchet wheel and clutch

members, a common transverse cylindrical casing arranged between said pawl casings, a rotatable locking member in said transverse casing, an operating arm on said locking member, and means for limiting the angular movement of said arm so that portions of said segmental portion are always in said pawl casings, and the whole assemblage effectively locked, said locking member having formed thereon circumferential grooves into which project portions of said pawls, said locking member also having formed therein a segmental recess which leaves a solid segmental portion the ends of which form abutments, shoulders on the outer portions of said pawls, said shoulders being adapted to abut against said abutments to withdraw said pawls alternatively from engagement with their respective teeth according to the position of said locking member.

8. The mechanism according to claim 1, comprising multiple plate clutch means interposed between said clutch member and said casing, said plate clutch means comprising non-rotatable plate means on said casing, other plate means rotatable with said shaft and further plate means rotatable with said clutch member.

9. The mechanism according to claim 1, comprising multiple plate clutch means interposed between said clutch member and said casing, said plate clutch means comprising non-rotatable plate means on said casing, other plate means rotatable with said shaft and further plate means constituted by the face of said clutch member adjacent said stationary plate means.
